CONTACT-BOMB.

1,318,956.

Specification of Letters Patent.

Patented Oct. 14, 1919.

Continuation in part of application Serial No. 195,609, filed October 9, 1917. This application filed May 27, 1918. Serial No. 236,916.

To all whom it may concern:

Be it known that I, LESTER P. BARLOW, a citizen of the United States, residing at New Haven, in the county of New Haven and 5 State of Connecticut, have invented certain new and useful Improvements in Contact-Bombs, of which the following is a specification.

My invention relates to bombs or the like 10 explosive bodies, and particularly to that type of bomb which is dropped or launched from an aeroplane and explodes on contact. It is well-known in such structures to maintain the detonator to the rear of the explosive chamber by means of an air-wheel 15 threaded on a rod extending from the rear of the casing. This wheel is rotated by the air when the bomb is dropped to unscrew the same from the rod to permit the detonator to drop into its firing position. Such 20 constructions are open to criticism in that the air-wheel and rod are exposed to the weather and may bind because of rust or other causes. The present application is in 25 large part a continuation of my application Serial No. 195,609, entitled Contact bombs, filed October 9, 1917.

My present invention aims to overcome 30 this difficulty by providing a weatherproof construction in which the detonator is released, after the bomb is launched or dropped, in a certain and efficient manner, which does not depend upon the action of the air. In my improved device, the detonator is normally 35 held or suspended at a safe distance to the rear of the explosive chamber, and means are provided to release the detonator upon the launching of the bomb, which means have a constant tendency to release the detonator 40 but may be restrained until the launching of the bomb, or which means may be rendered effective upon the launching of the bomb to coat with a fixed abutment, such as the casing wall, to break the suspending connection of the detonator. In the preferred 45 form of my device, the detonator is suspended by means of a pin extending through a portion of the same and the walls of the casing, a strong spring being provided to 50 withdraw the pin from the detonator when the bomb is launched.

My invention also comprises other im-

provements in devices of this character among which may be briefly mentioned the provision of a closure member for the explosive chamber, which is attached, in manner to be described, to the rear end of a forward casing member, and at the forward end of the rear casing member, when the device is finally assembled, a booster chamber and 55 guiding tube for the detonator being carried by the closure member or diaphragm mentioned. Other features include an air check device to retard the fall of the detonator into its firing position and the method of assembling the forward and rear casing members 60 hereinafter to be described.

In order that a clearer understanding of my invention may be had, attention is hereby directed to the accompanying drawings 70 forming part of this application and illustrating certain embodiments of my invention. In the drawings, Figure 1 represents a central longitudinal section through a bomb embodying my invention, Figs. 2 and 75 3 are cross-sections taken respectively on lines 2—2 and 3—3 of Fig. 1, and Fig. 4 is an enlarged sectional detail showing the junction of the forward and rear casing members.

Referring to the drawings, the bomb is provided with a forward casing member 80 designated generally as 1, which may be formed, for example, of sheet-metal members 2 and 3, suitably secured together, and a contact nose 4. The rear casing member is shown at 5 and joins the rear end of forward casing member 1, when the parts are assembled, in such manner as to give the entire casing a desirable stream line form.

The rear casing member 5 is generally 90 conical in form and is provided with a plurality of radially extending stabilizing vanes 6, integral therewith or suitably secured thereto, which vanes have portions 6' extending forwardly beyond the front open end of casing member 5 for the purpose of securing the front and rear casing members together, as will be described. The interior of the forward casing member may be filled 100 with high explosive 7, such as tri-nitro-toluol, and forms the explosive chamber of the device.

The detonator 8 may be of a desired form,

but is preferably an elongated cylindrical structure carrying detonating material 9 in a peripheral belt or pockets extending around the same midway of its length, as 5 described in my applications Serial No. 117,579, filed August 30, 1916, and Serial No. 150,712, filed February 24, 1917. A rear- 10 wardly extending portion 10 of reduced diameter is provided having a cylindrical opening therethrough through which loosely extends the pin 11, which also extends through the opposite lateral walls of casing member 5. This pin is provided at one 15 end with a head or enlargement 12, between which and the adjacent wall of casing 5 a spiral spring 13, coiled about the pin, is located. The opposite end of the pin 11 may be provided with a cotter-pin 14, which prevents withdrawal of pin 11. The wall of 20 casing 5 is preferably bent inwardly to form a vertical abutment 15 for the inner end of spring 13.

If the bomb is to be mounted horizontally below the aeroplane and released from a suitable trap, the cotter pin 14 may be used 25 merely for holding the pin in place during transportation and removed when the bomb is placed in the trap. In this case, the spring 13 is held under compression with the 30 head 12 of pin 11 pressing against a surface 16 of the trap indicated diagrammatically. When the bomb is released, the pin and 35 spring fall away from surface 16, whereupon spring 13 immediately expands against abut- 40 ment 12 to withdraw pin 11 and permit the detonator to fall. Spring 13 may, of course, be restrained until the launching of the bomb and then released by other suitable means, such, for example, as cotter pin 14, which 45 may be pulled out as the bomb is dropped, when the latter is mounted vertically.

Detonator 8 is suspended by the means described in the upper end of a guiding tube 17 which guides it to its firing position. A 50 booster 18 is preferably used with which is combined a closure or diaphragm for closing the rear end of the explosive chamber and thereby effectively separating the space in which the detonator is normally held from 55 the main explosive charge 7 and also from the booster charge. In the construction illustrated, the booster 18 comprises a metallic casting or frame having upper and lower cylindrical portions 19 and 20 which are connected by a plurality of radial portions 21 60 integral with cylindrical portions 19 and 20 and extending laterally beyond the same, as shown in Fig. 3. A thin tube 22 of brass or other suitable material is fitted within the 65 bores of cylindrical portions 19 and 20 to abut against the inner edges of the radial ribs or partitions 21. At the bottom of ribs 21 tubular portion 20 is provided with an annular outwardly extending portion 23, and at the top of the ribs a similar outwardly

extending annular portion 24 is provided. The space between ribs 21, tube 22 and top and bottom surfaces 24 and 23 may be filled with the booster charge 25 of high explosive, such as tri-nitro-toluol, which is confined in 70 position by mounting a metal tube 26 around the outside of the same, this tube being suitably secured to the booster frame as by peaning the lower edge of tube 26 to the metal of the annular portion 23. The upper horizontal portion 24 of the construction may have an annular upwardly extending portion 27 integral therewith which may be screw-threaded on its periphery. A ring 28 is 75 screw-threaded thereon, when the device is 80 assembled, and is of a suitable size and shape to fit within the rear and forward casing members adjacent the junction thereof. Ring 28 is adapted to be secured to the rear end of the forward casing member, and may 85 be provided with a peripheral flange 30, adapted to seat between the forward edge of member 5 and the rear edge of member 1, when the casing is assembled. Ring 28 may 90 also be secured to casing member 5, as by screws 29. The booster construction just described is adapted for use in other forms of explosive devices and is separately claimed in my application entitled "Booster construction for explosive devices", Serial No. 95 195,187, filed October 6, 1917.

The lower end of tube 22 within the booster may be closed by a suitable plug 31 carrying the firing pin 32. Tube 17, in which the detonator is normally supported, may be 100 mounted in position by screw-threading the lower end of the same into the upper tubular portion 19 of the booster frame. The bore of tube 17 is sufficiently larger than the diameter of the detonator to permit the detonator to drop rapidly through the same. Tube 22 at its upper end abuts against the lower end of tube 17 and forms a continuation thereof. Tube 22 flares inwardly 105 slightly at its upper portion, as shown at 33, and is, from this point to the bottom of the tube, of a smaller inner diameter which is only slightly larger than the greatest diameter of the detonator, a clearance of, for example, three thousandths of an inch being 110 provided. The bore of the booster frame is, of course, correspondingly shaped to form a suitable backing for this tube. When the bomb is launched or dropped and pin 11 released, the detonator falls rapidly until the 115 restricted portion of tube 22 is reached, after which the descent of the detonator through the tube is gradual as the air beneath the same slowly escapes around the periphery of the detonator. An air check is thereby 120 provided, so that in case the bomb came in violent contact with any object when it had dropped but a few feet from an aeroplane, the air cushion between plug 31 and the bottom of the detonator would prevent contact 125 130

between firing pin 32 and the fuse cap 34 in the bottom of the detonator. When, however, the bomb has dropped to a safe distance from the aeroplane, or point at which the 5 bomb is launched, the air beneath the detonator will have all or largely escaped, so that the detonator has been brought gently to rest upon or close to the firing pin and the contact of the bomb with its target causes the 10 successive firing of the detonator booster charge and the main explosive charge. It should be noted that the tube 22 is sufficiently thin to permit rupture of the same and detonation of the booster charge 25 when the 15 detonator charge 9 is fired, and that similarly booster charge 25 explodes outwardly into the main explosive charge 7 surrounding the same.

The stabilizing vanes 6 provided on the 20 rear casing member 5 extend forwardly beyond the forward edge of casing member 5, as stated, and are provided at their forwardly extending portions with angular extensions 35 adapted to contact the outer surface of the forward casing member 1. The forwardly extending portions 6' of the vanes are provided with forwardly extending slots 36, and the casing member 1 is provided with lugs or brackets 37 having screw- 30 holes therethrough.

When the bomb parts have been made, ring 28 is secured to the rear end of the forward casing member 1, preferably by positioning flange 30 on the rear edge of member 1, and welding the ring to member 1 just below flange 30, as is shown at 30' (Fig. 4). The booster construction is then screwed into ring 28, the closed booster with its outwardly extending flange 24 and the ring 40 28 making a complete closure for the magazine chamber of the bomb. In practice, the explosive charge 7 is then filled into place through the forward end of member 1, and the filling opening closed by nose block 4. 45 Tube 17, at this time or subsequently, is screwed into the tubular portion 19 of the booster frame.

The rear casing member 5 is equipped with the detonator suspended therein by 50 means of pin 11. In practice the member 5 with the detonator would not be secured to the forward casing member until after the magazine chamber had been filled with explosive, and member 5 with the detonator, 55 and the tube 17, need not be secured to the explosive-carrying front casing until after the parts have been transported to the place at which the bomb is to be used. When the bomb is to be finally completed, the forward 60 edge of the rear casing member is advanced against the rear edge of flange 30, detonator 9 being at the same time slipped into the rear end of tube 17, which has been secured in member 19 of the booster-closure member. 65 Screws are then passed through the screw-

holes in lugs 37 and slots 36 to draw the rear casing member firmly against flange 30 which is seated against casing member 1, and screws 29 may, if desired, be passed through member 5 into ring 28. 70

It will be observed that the construction described is simple in its design and method of assembly and is certain in operation. The construction may be made entirely weather-proof by filling the openings around pin 11 75 and the joint between flange 30 and member 5 with a suitable weatherproof wax or the like. When the detonator is in firing position, the detonation thereof can only take place outwardly into the booster charge 25, 80 the solid metal of the detonator above and below the detonator charge 9 preventing any of the detonating effect in the axial direction of the tube. Likewise the detonating effect of the booster charge is entirely outwardly because of the thickness of metal above and below the booster charge. In case the detonator is accidentally fired by any cause when it is suspended in its normal inoperative position, the explosive effect will 85 be nearly all expended outwardly without firing the main explosive or booster charges, the thickness of metal in the closure comprising members 19, 24 and 28 being sufficient to prevent detonation of these charges. 95

It will be understood that my invention is not limited strictly to the details described, but that a considerable range of equivalents is included within my invention as indicated by the accompanying claims. 100

What I claim is:

1. In a drop bomb, the combination of a casing having an explosive chamber, a detonator, means normally holding said detonator in the casing to the rear of said chamber, spring means constantly tending to free said detonator from said holding means, and permit the same to move toward said chamber, said spring means being adapted to be restrained until the bomb is 105 launched, means for firing said detonator at a point in its forward movement in the casing, and an air check device for retarding the movement of said detonator into the proximity of said firing means. 110

2. In a bomb or like body, the combination of a casing having an explosive chamber, a detonator, means adapted to normally suspend said detonator in the casing to the rear of said chamber, means for breaking the suspending connection of said detonator, means for firing said detonator at a point in its forward movement in the casing, and an air check device for retarding the movement of said detonator into the proximity 115 of said firing means. 120

3. In a bomb or like body, the combination of a casing having an explosive chamber, a detonator, means adapted to normally suspend said detonator in the casing to the rear 125 130

of said chamber, means for breaking the suspending connection of said detonator, a tube for guiding said detonator from its point of suspension to its firing position, said tube being closed at its forward end and having a diameter at its forward portion only slightly larger than that of said detonator, and a larger diameter at its rear portion, and a firing pin at the forward end of said tube.

4. In a bomb or like body, the combination of a casing having an explosive chamber, a booster mounted therein, a tube extending from the interior of said booster to the rear of said chamber, and a detonator normally mounted in the rear portion of said tube, and adapted to drop when the bomb or like body is launched, said tube having a diameter at its forward portion only slightly larger than that of said detonator, and a larger diameter at its rear portion, and being closed at its forward end.

5. In a drop bomb, the combination of a hollow forward casing member containing an explosive chamber and open at the rear, a hollow rear casing member open at the front, a booster suspended in the rear of said chamber and having a peripheral ring extension resting on the rear edge of said forward casing member, said extension being formed to provide a rearwardly extending seat of reduced diameter for said rear casing member, and means for securing said parts together to form a complete casing of stream-line form, with the forward edge of said rear casing member engaging against the rear surface of said ring extension, and fitting about said seat on said extension.

6. In a drop bomb, the combination of a hollow forward casing member containing an explosive chamber and open at the rear, a hollow rear casing member open at the front, and a diaphragm member for closing said chamber, having an annular flange portion resting on the rear edge of said forward casing member, peripheral seats of reduced diameter extending forwardly and rearwardly from said flange portion, and a central forwardly-extending detonator guide, closed at its forward end, said parts being adapted to be secured together to form a complete casing with continuous outer surfaces, the rear end of the forward casing member fitting about said forward peripheral seat, and the forward end of the rear casing member fitting around said rearwardly extending seat and engaging against the rear surface of said flange portion of said diaphragm member.

60 7. In a bomb or like body, the combination of a forward casing member containing an explosive chamber, a rear casing member having outwardly extending stabilizing vanes extending forwardly of its front edges, and means for securing the forwardly ex-

tending portions of said vanes to said forward casing member with said rear casing member in alinement with said forward casing member, said members being firmly secured together by said securing means.

8. In a bomb or like body, the combination of a hollow forward casing member, containing an explosive chamber and open at the rear, a ring secured within the rear end of said member, having a screw-threaded bore, and a frame screw-threaded into said ring to extend into said explosive chamber, containing a detonator-guiding tube, closed at its forward end, said frame and ring constituting a closure for said explosive chamber, said tube having an extension extending rearwardly from the rear edge of said casing member, a hollow rear casing member, open at the front, and means for securing said rear casing member directly to said forward casing member, in engagement with said ring and in alinement with said forward casing member.

9. In a bomb or like body, the combination of a hollow forward casing member, containing an explosive chamber and open at the rear, a ring secured within the rear end of said member, having a screw-threaded bore, a frame screw-threaded into said ring to extend into said chamber, containing a detonator-guiding tube, closed at its forward end, said frame and ring constituting a closure for said chamber, a guiding tube extending rearwardly from said frame as an extension of said first-named tube, a hollow rear casing member open at the front, adapted to be secured in alinement with said forward casing member, and a detonator removably suspended in the rear of said rear casing member from the walls thereof and inserted within the rear end of said removable guiding tube when the parts are all assembled.

10. In a drop bomb, the combination of a hollow forward casing member containing an explosive chamber and open at the rear, a hollow rear casing member open at the front, a closure for said chamber having an edge portion engaged by the alined rear edge of the forward casing member and forward edge of the rear casing member, the joint thus formed being sealed, said rear casing member having outwardly extending portions, and means for securing said portions to the forward casing member to secure said members together.

11. In a bomb or like body, the combination of a forward casing member containing an explosive chamber and open at the rear, a rear casing member, a closure for said chamber having an edge portion extending between the rear edge of said forward member and the forward edge of said rear member, the joint thus formed being sealed, said rear casing member having outwardly ex-

tending portions, and means for securing said portions to the forward casing member to secure said members together.

12. In a bomb or like body, the combination of a hollow forward casing member containing an explosive chamber, a closure for said chamber secured within the rear of said member, a tube extending rearwardly from said closure member, secured thereto, 10 and leading into said chamber, a hollow rear casing member, secured to said forward casing member, a detonator normally suspended in said tube with its rear portion extending rearwardly therefrom, and a pin 15 slidably extending through the walls of said rear casing member and the extension of said detonator to the rear of said tube.

13. In a bomb or like body, the combina-

tion of a hollow rear casing member open at the front, having stabilizing vanes extending outwardly therefrom and forwardly beyond the forward edge of the member, adapted to be secured to a forward casing member, a detonator, a pin slidably extending through the walls of said rear casing 20 member and a portion of said detonator, means removably holding said pin in position, and spring means tending to eject said pin.

This specification signed and witnessed 30 this 22d day of May, 1918.

LESTER P. BARLOW.
